CLAUDE E. BOWERS, OF LOS ANGELES, CALIFORNIA

DEVICE FOR SUPPORTING CONCRETE STEEL REINFORCING BARS

Application filed August 25, 1927. Serial No. 215,432.

This invention pertains more specifically to a device for supporting in steel reinforcing bars in position in the formation of concrete road-ways and the like.

5 In the formation of concrete road-ways reinforcing steel bars are employed to strengthen the same and prevent fractures, and as such bars must necessarily be placed in supported position prior to pouring the 10 concrete, it is therefore an object of the invention to provide a simple bar supporting member that may be conveniently placed in position along a road-way which will rigidly support in position a plurality of reinforcing bars during the concrete pouring operation.

A further object is to provide a reinforcing bar supporting device that may be accurately placed in position in a road-way 20 foundation without the necessity of employing measuring devices.

A still further object is to provide a device that may readily be die-stamped from sheet metal, and which will maintain the 25 reinforcing bars against accidental dislodgement during a concrete pouring operation.

The above and other objects are accomplished by means of the device described herein and illustrated in accompanying drawings, in which;

Fig. 1 is a plan view of a prepared road-way foundation showing the reinforcing bars in supported position.

Fig. 2 is a perspective view of a portion 35 of a road-way foundation showing a number of devices in position.

Fig. 3 is an enlarged sectional detail showing one of the bar supporting devices embedded in the finished concrete road-way.

40 Fig. 4 is a front elevation of the bar supporting device as shown in Fig. 3, before the concrete is poured.

In the construction of concrete roads the proposed road-way 5 is first excavated to the 45 required depth, usually about nine (9) inches and of the required width; in California such roads are about twenty (20) feet wide divided by a longitudinally extending score line 6 into two parallel sections 7, 8, each section 50 being transversely divided into sections 9.

Suitable planking 10 is erected along the outer longitudinal edges of the road-way, a centrally disposed planking 11 between the sections 7, 8, and cross planks 12 between the sections 9 of about one-half the width of the plankings 10. In order to strengthen the 55 concrete sections, and to prevent the formations of cracks therein it has been the practice to employ steel reinforcing bars 15 in the road sections. These bars must be supported in planes parallel to the road-way foundation before pouring the concrete, and to this end I have provided a simple die stamped metal bar supporting device that 60 will effectually maintain the reinforcing bars 65 in position and against dislodgement during the concrete pouring operation.

The bar supporting device 15 is here shown as consisting of a single piece of sheet metal die stamped or formed into the required 70 shape, preferably consisting of a prong shaped member 16 of generally channel form in cross section having a square upper end and a pointed ground penetrating end 17. Formed on one of the vertical flanges 18 of member 16 are a plurality of ledges or rod 75 seats 19, 20 and 21 for holding and supporting the reinforcing bars 15 in position within the road-way foundation. Each of the ledges have at their outer ends upwardly extending arms or lugs 22 for preventing accidental dislodgment of the reinforcing bars when placed thereon.

The lower end of the ledge 21 is provided with a right angled portion 23 that serves to 80 act as stop to limit the downward movement of the device when driven into position.

In order to space the devices the required 85 distance from the road-way plankings, the central bar supporting ledge 20 has an arm 24 pivotally secured thereto, the free end of the arm being bent at right angles to form an attaching lug 25 provided with a nail hole. This arm serves not only as a means for bracing and attaching the device to the inner surfaces of the plankings, but serves also as a gage for spacing the supporting devices a predetermined distance from the planking, 90 see Figs. 2 and 3 of the drawings.

100 In using the bar supporting devices in road

building about eight are required for the sides of each section, and four at each end, but this number may be varied according to the weight of the reenforcing bars employed.
5 Usually only a pair of reenforcing bars are used for each slab section in road-ways of normal depth, but should the depth be increased the ledge 20 can be used.

The concrete surface is scored transversely as at 26 directly above the cross plankings in order to form weakening planes, the concrete breaking at such points instead cracking intermediate the ends of the slab sections.

From the above description it will be apparent that I have provided a simple bar supporting device that is of inexpensive manufacture, and one that may be quickly placed in position along the road-way without the necessity of employing measuring devices of any character.

What I claim is:

1. In a device of the class described an earth penetrating prong of generally channel form in cross section having a plurality of 25 horizontally disposed rod seats formed on one of its side flanges die stamped from a single sheet of metal, the prong having a pointed lower end, means formed on the lowermost rod seat to limit ground penetration, and a pivoted bar or arm secured to said prong, one end adapted to be attached to an object to stabilize said prong when in position.

2. In a device of the class described an earth penetrating prong of generally channel form in cross section having a plurality of horizontally disposed rod seats formed on one of its side flanges die stamped from a single sheet of metal, the prong having a pointed lower end, the metal of the lowermost rod 40 seat being bent at right angles thereto to form a stop to limit the earth penetration of the prong, and a pivoted bar or arm secured to said prong, one end adapted to be attached to an object to stabilize said prong when in position.

3. In a device of the class described an earth penetrating prong having a plurality of horizontally disposed rod seats formed on one of its side edges, means formed on the lowermost rod seat to limit ground penetration of said prong, and a pivoted bar or arm secured to said prong, one end adapted to be attached to an object to stabilize said prong 50 when in position.

In testimony whereof I affix my signature.
CLAUDE E. BOWERS.
